FIG. 6

UNITED STATES PATENT OFFICE

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

APPARATUS FOR HANDLING ORE AND THE LIKE.

Application filed October 10, 1921. Serial No. 506,711.

To all whom it may concern:

Be it known that I, CHARLES E. DAVIS, a citizen of the United States, residing at Chicago, in the county of Cook and State of Illinois, have invented an Improvement in Apparatus for Handling Ore and the like, of which the following is a specification.

This invention relates to improvements in apparatus for handling ore and the like and has for its principal object to provide an improved apparatus for transporting loose material from one place to another, as for instance in a mine.

In two prior applications, Serial No. 382, 15 696, filed May 20, 1920, and Serial No. 460, 865, filed April 13, 1921, I have disclosed devices of the class above described comprising a scraper and a movable frame adapted to form a support about which said scraper 20 is guided. In the present application, I utilize the same general principles of construction and operation as described in the above-mentioned applications, but provide certain improvements in the construction of 25 the scraper as will hereinafter more fully appear.

My invention may be best understood by reference to the accompanying drawings, in which Figure 1 is a top plan view of my 30 improved apparatus in working position in a mine.

Fig. 2 is a side view of the apparatus shown in Fig. 1.

Fig. 3 is an enlarged top view of the 35 scraper made in accordance with my invention.

Fig. 4 is a cross-section of the scraper taken on line 4—4 of Fig. 3.

Fig. 5 is a cross-section of the scraper 40 taken on line 5—5 of Fig. 3.

Fig. 6 is an enlarged detail plan view of a casting forming a portion of the scraper.

Fig. 7 is a cross-section taken on line 45 7—7 of Fig. 1 showing the arrangement of the lateral bearing means carried by the scraper and engaging with the main frame of the scraping apparatus.

In the embodiment of my invention illustrated, the apparatus is adapted for use in mining operations in which loose material is to be transported from the working face, or place from which the material is being mined, to a place where it may be loaded 50 on mine cars. The apparatus comprises a

scraper 1 adapted to be moved on the mine bottom by means of flexible draft cables 2 and 3, and about a guiding frame 4 fixed on the mine bottom in position to form a bearing for one side of the scraper as the latter is advanced into the loose material. The frame 4 is held in place by means of a guiding device, such as a pair of mine jacks 5 and 5^a of the usual type which are inserted in a longitudinally disposed slot 6 formed in the frame. The jacks 5 and 5^a are spaced apart so as to guide the movement of the frame in a longitudinal direction. The frame may be moved longitudinally by any suitable means such as a draft 70 device attached to one of the jacks. In the embodiment illustrated the draft device comprises a rope 11 hooked to the forward jack 5 and operated by a ratchet wheel 8 mounted at the rear end of the frame. Said ratchet wheel is connected with a drum 10 about which the rope 11 is wound, and is adapted to be manually operated by the handle 9. By means of this construction the entire frame is movable in a longitudinal direction on the mine bottom so as to advance the scraper 1 as desired.

The head frame 4 forms the subject of a separate application Ser. No. 506,712 filed by me Oct. 10, 1921, and has as its principal features an arcuate shield or bearing member 12, a pair of longitudinally disposed beams 13, 13, a rear end member 14 on which the ratchet mechanism for advancing the frame is mounted, and suitable side frame members 15 and 16 connecting the shield 12 with the rear end member 14. The curved or bearing face of the shield 12 is provided with a centrally disposed recess or groove 17, a substantially vertical bearing surface 18 above said recess, and an outwardly and downwardly extending bearing surface 19 below said recess. A plurality of sheaves 20, 20, are arranged about the shield and in line with the recess 17. The arrangement is such that the draft ropes 2 and 3 are adapted to engage within the recess 17 and bear on the sheaves 20, 20, as the device is operated. Further details of the head frame need not be described for the purpose of 100 understanding the present invention, which relates particularly to the scraper.

Referring now to the scraper, details thereof are shown in Figs. 3 to 7 inclusive, which illustrate a preferred form which I 110

find to be particularly adapted for use with an apparatus such as hereinbefore described. In general conformation and outline this scraper is similar to those disclosed and claimed in my prior applications hereinbefore mentioned, that is to say, the scraper is bottomless, and is provided with a curved inner wall 21 adapted to conform substantially with the curved shield 12, and a curved outer wall 22 having upright forward margin 23 forming the cutting edge of the scraper as it enters the loose material. My improved form of scraper illustrated herewith is provided with a plurality of anti-friction members 25, 25, adapted to engage the arcuate shield 12 while the scraper is being moved thereabout. In the embodiment shown, four of these anti-friction members are provided. Two of these are arranged adjacent the forward end of the scraper, one being arranged above the centrally disposed slot 17 and engaging the bearing face 18, and the other arranged below said slot and engaging the outwardly inclined bearing face 19 of the head frame 4, as shown in Fig. 7. The second pair of anti-friction members or rollers 25, 25, are mounted adjacent the rear end of the scraper, above and below the recess 17, as in the case of the first pair of friction members. It will be understood, however, that any suitable arrangement of anti-friction members may be provided as desired in order to afford the scraper substantial lateral bearing on the shield as it passes about it.

The anti-friction members 25, 25, are each preferably mounted in a housing 26, set into the side wall 21, and closed to the interior of the scraper, as shown in Fig. 7.

The scraper body is constructed of a plurality of parts, the principal parts comprising an inner wall portion 21^a, an outer wall portion 22^a, and a rear bottom piece 30. The side portions 21^a and 22^a are preferably of sheet metal, and jointed together at the rear of the scraper above the rear bottom piece 30, as shown in Fig. 2. Said bottom piece 30 is irregular in shape, as shown in the cross-sections in Figs. 4, 5, 6 and 7, and includes a rear wall portion 31 inclined forwardly and downwardly and terminating in a cutting edge 32, adapted to rest on the mine floor. The bottom portion 30 is preferably made of a casting, owing to

its having such an irregular form, and furthermore, being subject to considerable wear. The forward edge 23 of the outer wall 22 is provided with a wearing member 23^a, and the lower margins of the walls 21 and 22 are also provided with inwardly extending wearing strips 21^b and 22^b, respectively. By reason of the construction just described, the scraper may be economically made of relatively light material, but provided with suitable heavy wearing pieces where necessary.

Although I have shown and described one form in which my invention may be embodied, it will be understood that many other means may be employed for accomplishing the same results without departing from the spirit and scope of my invention. I do not therefore wish to be understood as limiting myself to the specific construction illustrated herein excepting as specifically limited in the appended claims.

I claim as my invention:

1. In an apparatus of the class described the combination of a guiding frame adapted to be fixed against lateral movement, and having a curved bearing portion, and a draft-operated scraper having a plurality of anti-friction rollers mounted on one side thereof and adapted to engage said curved bearing portion.

2. In an apparatus of the class described, the combination of a frame having a curved bearing portion, a draft-operated scraper having one side thereof curved to conform substantially with said curved bearing portion, and a plurality of anti-friction members mounted on said curved side of the scraper and adapted to engage said curved bearing portion.

3. In an apparatus of the class described a bottomless scraper comprising a rear end piece formed of a single casting having a forwardly and downwardly extending rear wall portion, horizontally-curved side walls formed of sheet metal and secured to said casting, and inwardly-extending wearing members secured to the bottom margin of said side walls forwardly of said casting.

Signed at Chicago, in the county of Cook and State of Illinois, this sixth day of October, 1921.

CHARLES E. DAVIS.
